UNITED STATES PATENT OFFICE.

JOHN M. LEWIS, OF BLANCHE, ALABAMA.

STEAM-COOKER.

No. 906,245.

Specification of Letters Patent.

Patented Dec. 8, 1908.

Application filed July 27, 1908. Serial No. 445,591.

To all whom it may concern:

Be it known that I, JOHN M. LEWIS, a citizen of the United States of America, and a resident of Blanche, in the county of Cherokee and State of Alabama, have invented certain new and useful Improvements in Steam-Cookers, of which the following is a full and clear specification, reference being had to the accompanying drawings, in 10 which—

Figure 1 is a vertical longitudinal sectional view; and, Fig. 2 is a vertical transverse section taken on the line 2—2 of Fig. 1.

The object of this invention is to provide a 15 simple apparatus for steaming and boiling canned vegetables and fruits, and the invention consists in certain novel features of construction hereinafter described and claimed.

A designates the furnace which may be 20 constructed of masonry or of iron, and supported in this furnace is the boiler which consists of a series of compartments or vats, the central vat B being considerably deeper than the two end vats C, and each vat being 25 provided with a removable cover and suitable horizontal crate-supporting bars D.

The boiler is set down partly into the furnace and is preferably constructed of sheet metal and is supported within the furnace by 30 two arched bars E attached to the opposite side walls of the boiler and having their ends resting upon the top of the furnace. A space is formed around the sides and rear end of the boiler so that the products of combustion 35 practically envelop the lower half of the boiler, thus obtaining a maximum heating capacity. To still further increase the heating capacity of the furnace the products of combustion are caused to pass forwardly 40 through two or more large tubes F extending entirely through all the vats and opening into a smoke-box G at their forward ends at the front of the furnace just over the furnace door. The front wall of this smoke-box is 45 hinged at H so that it may be opened to permit the smoke - box and the flues to be cleaned.

It will be observed that the top wall of the smoke-box is formed by the bottom of the 50 supply-tank while the back wall thereof is formed by the front wall of the boiler proper, whereby the heat of the products of combustion is utilized to a maximum extent before escaping up through the smoke-flue; and it 55 will be further observed that by hinging the front wall of the smoke-box at its upper end

and inclining it toward the boiler the smoke-box may be cleaned expeditiously as it will simply be necessary to unfasten the lower edge of the door and swing it downwardly 60 and away from the boiler whereupon the accumulated soot will fall into a receptacle placed or held below.

The products of combustion pass from the smoke box up the stack I, surrounding which 65 is a water-supply tank K, the object of this being to utilize the waste products of combustion to preliminarily heat the water to be supplied to the vats. The tank K is connected to the several vats by a suitable ar- 70 rangement of valved pipes L so that the water from the tank may be run into the vats separately, thus permitting the level of water in each tank to be kept at the point desired. A suitable arrangement of pipes M is 75 employed to drain the vats.

By reason of the manner of supporting the boiler on the furnace a strong and rigid structure is obtained and furthermore the boiler, together with the water-tank, the tank being 80 permanently attached to the forward end of the boiler, may be readily removed entirely from the furnace to permit the boiler and the furnace to be separately repaired and cleaned.

The central vat is made deeper than the 85 others in order that it may be used for steaming the cans preparatory to sealing them in the usual manner. The cans are first steamed in the usual manner in the central vat and after being removed and sealed they 90 are placed in the end vats for boiling and inasmuch as they come from the steam vat hot they will not materially reduce the temperature of the water in these boiling vats. The larger capacity of the central vat enables it 95 to accommodate enough cans to supply both the other vats, so that with a single steaming vat the operation of the apparatus may be continuous.

Having thus fully described my invention, 100 what I claim as new, and desire to secure by Letters Patent, is:—

1. In combination, a furnace, a boiler supported therein and consisting of a series of vats and fire flues extending from the back of 105 the boiler to the front thereof through the vats, an elevated supply-tank supported upon the forward end of the boiler and having valved pipe connections with the various vats and having a smoke-flue extending up 110 through it, and a smoke-box formed at the junction of the boiler and the bottom of the

J

supply-tank, the bottom of the supply-tank and the front wall of the boiler thus forming two walls of the smoke-box, and the front wall of the smoke-box being hinged to the 5 bottom of the supply-tank and inclined toward the boiler, for the purpose set forth.

2. The combination with a furnace, a boiler set down in the top of the furnace, a pair of arched bars fastened to the opposite sides of 10 the boiler and having their ends supported

on the furnace walls, said boiler being divided up into a series of vats.

In testimony whereof I hereunto affix my signature in the presence of two witnesses this 24 day of July 1908.

JOHN M. LEWIS.
